UNITED STATES PATENT OFFICE.

FRANK WILCOMB, OF NORRISTOWN, PENNSYLVANIA, ASSIGNOR TO HEMPHILL MANUFACTURING COMPANY, OF CENTRAL FALLS, RHODE ISLAND, A CORPORATION OF RHODE ISLAND.

CIRCULAR-KNITTING MACHINE.

1,129,261.

Specification of Letters Patent. Patented Feb. 28, 1915.

Application filed December 13, 1913. Serial No. 206,580.

To all whom it may concern:

Be it known that I, FRANK WILCOMB, citizen of the United States, residing at Norristown, Pennsylvania, have invented certain new and useful Improvements in Circular-Knitting Machines, of which the following is a specification.

My invention concerns more particularly the yarn feed mechanism and the controlling connections therefor, by which the efficiency of the machine is generally enhanced and the number of yarns which may be fed to the machine is increased.

The invention also includes other features hereinafter referred to.

The invention consists in the features and combination and arrangement of parts hereinafter described and particularly pointed out in the claims.

20 In the accompanying drawings: Figure 1 is a front view of a machine embodying my invention; Fig. 2 is a side view looking from the left of Fig. 1; Fig. 2^a is a detail plan view of the lifters for the yarn fingers; Fig. 25 3 is a plan view of the machine; Fig. 4 is a detail sectional view of the latch ring in its relation to the knitting head and showing the yarn fingers and connections; Fig. 5 is a plan view of the yarn feed finger organization; Fig. 5^a is a front view of the mouth piece of Fig. 5, and in this view all the yarn fingers are represented for convenience in their lowered position. In running the machine, however, it will be understood that the yarn fingers collectively would not assume this position and would do so only when the latch ring, in which they are supported, is raised; Figs. 6 and 7 are views of a plating plate; Fig. 7^a is a view of a modified form of plating device. Figs. 8, 9 and 10 are views of details; Figs. 11, 12 and 13 are views of the connection between the levers and their operating wires or links. Fig. 14 is a view of a detail.

45 The yarn feed fingers marked 1 to 6 are of substantially the same form as those used on the Banner machine built under Letters Patent of the United States granted to Hemphill, 933,443, September 7, 1909, but 50 my yarn finger organization as a whole, including their number, arrangement, mounting and their operating connections, is a development of and an improvement upon the Banner machine designed to give increased 55 efficiency, wider scope of variations in yarn

feeding, and to enable the machine to be handled with greater facility and more readily assembled, repaired, or dismantled.

In the Hemphill machine as shown in Figs. 5 and 27 of the patent, referred to, a 60 yarn feeding opening or mouth piece C' is used through which the yarns are delivered to the needles from yarn fingers which occupy the mouth piece from wall to wall. This is a desirable form of yarn feeding 65 means for machines of the Hemphill type. This mouth piece or opening is formed in the latch ring C of the Hemphill patent, and its width is necessarily restricted to certain narrow limits for various reasons, one 70 being that if a wider mouth piece were used the cams for operating the needles would have to be situated at a considerable distance apart, and on reciprocating knitting the reciprocations of the machine would be 75 so long that production would be greatly reduced from that which has now become standard. Further, the wider separation of the cams for the needles would necessitate such change in the location of the picks that 80 one set would interfere with another. Again, the delivery of the yarn to the needles by a wide mouth piece can not well be controlled when plating is being done, or heel and toe knitting is being performed. 85 A narrow yarn delivery mouth piece has been found in practice to be necessary. Where, however, a narrow mouth piece is combined with yarn feed fingers, as in the Hemphill patent, the number of yarn fingers 90 that can be employed is very limited. Three are shown in the patent. These completely fill the mouth piece from wall to wall.

One object of my invention is to provide in connection with a mouth piece as narrow 95 as that of the Hemphill machine a larger number of yarn fingers, individually of normal width or size adapted to receive the ordinary diameter of yarn guide hole.

In carrying out my invention as to the 100 yarn fingers, the finger 5 for the heel and toe yarn is arranged in the center of the mouth piece C' or approximately so, this being on the radial center of the machine. When, therefore, heel and toe pockets are being 105 formed, the yarn is fed by the finger to either one corner or the other of the mouth piece in precisely the same manner, as in common practice. This may be the only 110 yarn finger or carrier which handles yarn

during reciprocating knitting as for heels and toes. All the fingers throw the yarn into or out of engagement with the needles while the machine is turning in the direction for round and round knitting, going from left to right or reverse of clockwise in the arrow direction, Fig. 5, and I have found that by making certain improvements an indefinite number of additional yarn feed

10 fingers may be used, placed off the radial center of the head, and lying as a group in a direction opposite to the direction of turning movement of the machine during round and round knitting. The yarns from these 15 fingers are fed into the narrow mouth piece to be directed thereby as successfully as though all the fingers were fitted into the mouth piece in the usual way.

Figs. 3 and 5 illustrate the off-center arrangement of the yarn fingers. While the mounting of the yarn fingers may be accomplished in various ways, in the particular construction shown, they are mounted in an enlarged chamber 7 in rear of the mouth piece, said chamber lying partly in rear of the front wall 8 which defines one side of the mouth piece. This front wall lying to one side of the feed mouth C' is surmounted by a guard portion 9 which inclines downwardly and toward the center of the mouth piece, so that any yarn striking thereon when either of the yarn fingers, such as 1, 2, 3 or 4, is lowered, will be directed into the feed mouth to be delivered thereby to the needles.

35 When any yarn finger is lowered, as for instance, #5, Figs. 3, 5 and 5^a, the yarn therefrom will be delivered through the mouth piece opening to the needles, the yarn running against one of the shoulders 10 according to the direction of rotation of the needle cylinder. The mouth piece has inclined edges 11 for opening the latches of inoperative elevated needles, and a latch guard 12 to prevent the closing of the 45 latches of those needles which are knitting.

The yarns which are out of work are held, as in common practice, by a clamp device 13, Fig. 5, within the needle circle. The construction of this clamp may be of any desired form. The one shown is similar to that well known as used in the Banner machine, and therefore needs no particular description. Only so much of it is shown as to indicate its general function and position.

55 It will be observed, Fig. 5, that the inoperative yarns extend from the yarn fingers to this clamp at an angle, the incline being in the direction of rotation of the cylinder in round and round knitting, and as above stated, it is only during round knitting that the yarns from the "off center" yarn fingers 1 to 4 are brought into use. It will be seen by this arrangement that when either of the "off center" yarn fingers, *i. e.*, those lying to

65 the right of the radial center of the ma-

chine, is lowered to throw its thread into work, the inclined relation of this yarn will cause it to fall into the narrow mouth piece, this effect being insured by the inclined guard or guide 9. This result will be accomplished notwithstanding the fact that the yarn finger may be located, as, for instance, 1, out of line with and considerably to the right of the mouth piece.

The incline of the yarn just mentioned from the yarn finger to the needles is in the direction of rotation of the needle circle. The narrow yarn feed mouth and the means for guiding the yarns thereto from a series of yarn fingers of such number or arrangement as to preclude the location of them all in line with the mouth piece may be variously organized, but in the application of this part of my invention to the Banner machine I prefer the arrangement described above. In this yarn finger organization I have also associated a plating or yarn separating plate or finger A shown in detail in Figs. 6 and 7 and shown in place among the yarn fingers in Figs. 3, 4, 5 and 5^a. This is arranged adjacent the yarn finger 4 which has the two guide eyes for the main and plating yarns. This plating plate has a bar 14 and a slot 15, both inclined downwardly and outwardly in relation to the center of the machine. The main and plating yarns are fed through the separate holes in yarn finger 4 and one of these yarns passes through the opening in the plating plate and the other passes around the front side of the bar 14, these threads being indicated at *x* and *y* in dotted lines in Fig. 6 in the out of work position, *i. e.*, elevated above the needles which are raised to take the yarn.

The lowered position of the yarns is indicated in full lines at *x'* and *y'*. These yarns, when in this lowered position, are in work and after leaving the plating plate they meet at the lower corner 10 of the mouth piece where the needles engage them for knitting. The purpose of this plating plate or finger is to widely separate the main and plating yarns and prevent one yarn from matting with or attaching itself to the other as they pass side by side to the point where they are taken by the needles for knitting, thus insuring that the yarns will be laid in the fabric in the proper relation to bring the desired yarn on the face of the fabric instead of first one and then the other indiscriminately. This plating plate lies over the latch guard or ledge 12, and to prevent the yarn from being caught in the crevice between its lower edge and the surface of the ledge, a guard or projection 15' is provided on the plating plate extending down into an opening in the ledge or base of the mouth piece, so that the yarn, when lowered into work, will rest against the front inclined edge of the bar near the top sur-

face of the ledge 12. The incline of the slot and the front bar is provided to conform substantially to the path described by the yarn in its raising and lowering movement. 5 The yarn fingers are pivoted above the plating plate, which guides and separates the plating yarns, and the incline of the slot and the front guiding bar of the plate approximates the arc in which the end of the 10 plating yarn finger 4, with its yarns, swings. This construction allows the yarn to be shifted freely from one position to the other. This plating plate is reduced at its front end to prevent the yarn from being 15 pinched between it and the adjacent yarn fingers in raising and lowering.

The yarn fingers are normally under tension of spring elements tending to press them downwardly, and they are raised by 20 connections positively operated from a cam wheel hereinafter referred to. The spring pressed elements consist of levers 16 pivoted at 17 in rear of the pivot 18 of the yarn fingers, Figs. 4 and 5. These levers are pressed 25 upwardly by spring plungers 19 seated in the latch ring C. The spring levers engage shoulders on the hubs of the yarn fingers close to and in rear of their pivots, and press upwardly, and therefore press the yarn 30 carrying ends of the yarn fingers normally downwardly. These yarn carrying ends must describe an arc of considerable length in moving the yarns into or 35 out of work. As it is desirable to employ short springs and prevent deadening them, I arrange the parts so that only a small movement of the spring levers will be needed to give the longer movement at the yarn carrying ends of the yarn fingers. For this 40 reason the point of engagement between the yarn fingers and the spring levers is as near the pivot of the yarn fingers as is possible.

It will be seen from Fig. 4 that very little movement will be imparted to the spring 45 levers and their springs by the lifting of the yarn fingers, and thus undue compression of the springs will be avoided. The hubs of the yarn fingers are provided with shoulders or lugs 20 for the spring levers to 50 engage with, and above these the hubs have portions concentric with the pivots. Therefore, when it is desired to thread any yarn finger, it can be thrown upward and backward still farther from the raised or inoperative 55 position shown in Fig. 4, so that the thread can be readily introduced through the eye. Little or no additional compression of the spring will result in this action and the spring lever, by bearing on the concentric 60 part of the hub of the finger, will serve to hold it under frictional restraint in the position to which it has been moved.

The whole assemblage of yarn fingers and 65 plating plate is mounted on the latch ring C of substantially the same general form

as is commonly used in the Hemphill construction. This latch ring is pivotally mounted at 21 at the rear of the machine, the ring having an arm 21' lying between the bifurcated end of the standard 70 22. This construction is to permit the latch ring with the yarn fingers mounted thereon to be swung up and back to expose the needle circle for the transfer of tops or for other purposes. 75

To hold the ring in its lowered working position, a self locking catch 21* is employed pivoted to the standard 22 which supports part of the yarn finger operating connections, as will be presently described. 80 This catch is pressed by a spring 22' mounted in a recess in the post. The catch has a cam shaped point 23 which, as the ring is lowered into working position, will ride against the surface 24 of the ring, resulting 85 in the pressing back of the catch until the low position of the latch ring is reached, when the catch will spring forward and retain the latch ring down. The low or working position of the latch ring is determined 90 by a screw stud 24* thereon coming against the top of the bracket or standard 22*, and this stud is adjustable to accurately locate the catch. The cam shaped point 23 of the catch enables it to accommodate itself to 95 different adjustments of the latch ring. The catch has a finger piece by which it may be pressed back for releasing the latch ring.

The yarn fingers may be elevated by various forms of devices within the scope of my 100 invention, but in the particular form shown a series of vertically sliding lifters are employed in the form of plates 25, which are guided in a box-like structure 26 at the top of the standard 22*. The number of lifter 105 plates is equal to the number of yarn fingers which are to be raised out of and lowered into work, and these lifters are spaced apart and guided by plates 27, one of which is shown in Fig. 2*, and both of which are 110 shown in section in Fig. 4. These plates are channeled on their inner faces to receive the edges of the lifter plates. Each lifter plate has a forward extension 28 which engages with the lower edge of the appropriate 115 yarn finger, Fig. 4, and each lifter has a projection 29 depending therefrom. These projections are arranged in echelon to be engaged by the contracted or convergent ends of levers 30 pivotally mounted on a 120 pin 31 projecting laterally from a post 32 and removably mounted on said post to enable the levers to be dismantled. The ends of the levers are, of course, arranged step-wise to correspond with the echelon arrangement of the projections 29, the levers being of different lengths as shown in Fig. 125 3. Referring to this Fig. 3 and to Fig. 2, the front of the machine is at the right of these figures, as will be seen in Fig. 1 also. 130

which represents a front view of the machine. The Banner machine of the Hemphill construction has the cam shaft s' at the front lower part of the machine, this shaft 5 having cams mounted thereon which control the operation of the yarn fingers and other parts of the machine such as the means for changing from round to reciprocating knitting, including inclines or projections on a 10 cam drum f for operating the clutch lever b' , a cam member g for operating the vertically guided rod g' which is connected with the plate H carrying the needle cams and the narrowing picks R , the finely toothed 15 ratchet c , the coarse toothed ratchet e , the sprocket wheel d , and the pattern chain B . The location of this cam shaft with the parts carried thereby at the front of the machine is a desideratum in that all said parts 20 are under observation of the operator and within easy reach for his attention, and are readily accessible to the "fixer" should occasion arise to repair or adjust the parts.

In carrying out my invention wherein I 25 am able to secure the employment of a larger number of yarn fingers than heretofore employed in machines of the type referred to, I have aimed to preserve the general desirable characteristics of the existing machine 30 and to a greater degree secure accessibility to the operating connections than has been possible heretofore, and to do this without changing the framework of the Hemphill machine or the general arrangement of its 35 parts. In the Hemphill machine the yarn fingers are operated by levers f' , mounted within a box or standard K , see the patent mentioned, and operating wires or rods lead from these levers down through the box and 40 through the top plate to the interior of the frame of the machine to connect with cam operated levers f'' . The wires are connected to the yarn finger operating levers by hooks on the wires engaging the said levers, 45 and because of this and the inaccessibility of these parts it has been difficult to assemble or to disengage the parts which must at times be done. In my construction the vertically movable lifters 25 for the yarn fingers 50 are interposed between the yarn fingers and their operating levers 30 , but are not connected to either, simply resting by gravity in their guide ways of the boxing 26 , and bearing upon the ends of the levers 30 . 55 By lifting the latch ring and thus removing the yarn finger organization from over the boxing 26 , the lifters 25 may be dropped into position or exposed for removal by raising them. The operating levers are not inclosed, 60 but as previously stated they are pivoted in exposed position on the pin 31 mounted in a post 32 . They extend at right angles to the yarn finger organization and lifters 25 , and to the front of the machine, and their forward ends are connected by links or wires 65

f'' to the cam operated levers f'' . A pair of these levers 30 with their connections are arranged at the right of the post 32 , and their links extend to levers f'' operated by cam pieces on the cam drum f . The other 70 levers 30 , four in number in this case, are operated from cam pieces on a drum f'' which is arranged outside the usual frame work of the Hemphill machine, being located on the shaft s' . The wires or links 75 for operating these levers are arranged entirely outside the frame and extend down the front side thereof, as shown in Figs. 1 and 2, and connect at their lower ends with the levers f'' which are operated by the cam 80 pieces on the cam drum. The levers 30 are operated in one direction by the springs $30''$, that is, these springs lower the levers when the cam drum presents a low part to the cam lever f'' . 85

In order to make a connection between the wires or links f'' and the levers which will be free from lost motion and will therefore serve to transmit the movement with accuracy and at the same time provide 90 for the ready assemblage of the levers and links or their dismantling and without requiring skilled operators, I have devised the hook and pin connection shown in Figs. 11 and 12. 95

The levers 30 have bifurcated ends with pins 33 fixed rigidly therein by riveting, soldering or in any suitable way to make them a permanent part of the levers. The links or wires have heads 34 notched to receive the pins, the notches extending at right angles or laterally to the axis of the wires. These heads have their ends formed on an arc struck from the center of the pins 33 and the distance from the center of the pin 100 to the wall 35 at the bottom of the fork or bifurcation of the lever 30 being equal to the radius of the arc on which the end of the head is struck, it will be seen that when the lever and its wire are in working 105 relation, i. e., approximately at right angles to each other, Figs. 2 and 11, the link will be locked in engagement with the pin and held firmly seated in connection therewith, because the wall of the fork forms a backing or bearing for the link head and there will be no lost motion or play between these parts. 110

In order to assemble them or separate them from each other, the levers and links 120 are moved into alinement, as shown in Fig. 12, so that by a lateral movement of one in relation to the other they may be separated or assembled. When in working relation there is no possibility of the levers and links becoming disconnected. To dismantle the lever and link organization, the pivot pin 31 must be removed. The same kind of connection exists between the lower ends of the wires or links f'' and the cam levers f'' . 125 130

The connection described not only enables ready dismantling or assembling of the links and levers, but being devoid of lost motion chattering of the yarn fingers is prevented, overthrow avoided, and wear reduced. The ends of the levers 30 are guided in a grating shown in dotted lines, Fig. 4.

Reverting to the yarn fingers, the one marked 6 is used for feeding a reinforcing yarn to reinforce the fabric, or to feed a supplementary yarn to approximately half the needle circle. This is operated at each half revolution of the machine by a forked lever 36, Figs. 1, 2^a, and 3, engaging a pin 37 projecting from the rear face of the yarn finger lifter plate 25. This forked lever is operated by a link 38, a rock shaft 39, dotted lines, Fig. 1, and an arm 40 thereto operated by a cam 41. When the 20 yarn finger 6 is to be made inoperative, the appropriate lever 30 is operated by the fashioning drum 7, and the lifter plate 25 is raised to lift the yarn finger. This lifting of the plate 25 will move the link 38, shaft 39 and arm 40 out of the range of the cam 41.

The fashioning fingers 42, 43 and 44 are of special arrangement. They are arranged in a boxing g^2 and are operated upon by cam projections g on the fashioning drum f to control the position of the cam carrying plate H by means of the vertically guided rod g^3 . These fingers, therefore, in connection with the cams working thereon, effect the adjustment of the cams for tight or loose knitting at different points in the fabric, as is well known in connection with hosiery machines. These fingers consist of flat plates moving in channels 45 in the boxing g^2 , which channels are closed at the front to hold the fingers thereon by a cover plate 46. The channels extend through from top to bottom of the boxing, and each channel has a counter-bore 47 reaching from its upper end part way down the boxing, leaving a ledge at 48 upon which rests a spiral spring, or rather a head 49 of a rod 50 for centering the spring. The finger plates are recessed in their front edges to receive the springs and rods, and these springs press upwardly on the fingers and keep them raised against the screws 51. These screws are mounted in the top of the cover plate and by adjusting them the position of the fingers in relation to the fashioning plates on the drum may be accurately determined.

I have shown a pick for controlling the needles, this being of novel construction, but this is to be made the subject of another application.

In Fig. 7^a I show a modified form of plating device consisting of a wire attached at one end to a plate like that shown in Fig. 6, and at its other end attached to

the bottom of the mouth piece. The main thread passes on one side of this and the plating thread on the opposite side.

I claim as my invention:

1. In combination in a circular knitting machine, latch needles, a needle cylinder, a yarn feed mouth having latch opening side walls and a series of yarn fingers occupying as a group a greater space laterally than the width of the mouth, some of the fingers being adapted to travel through the mouth, and means for directing the yarn from all the fingers into the narrow yarn feed mouth, substantially as described. 70

2. In combination a rotary and reciprocating needle cylinder, latch needles, a latch opening mouth piece for directing the yarns to the needles, a series of yarn fingers, said mouth piece being narrower than the combined width of the ends of the yarn fingers, 85 and a guide inclining downwardly to the mouth piece for directing the yarn thereto, substantially as described. 80

3. In combination in a latch needle knitting machine having a reciprocating needle cylinder, a mouth piece with downwardly diverging side walls, the lower side of said mouth piece being wider than the top, the diverging walls serving to open the latches of the needles and a group of thread fingers 95 adapted to feed the yarn to the needles, said group of yarn fingers having a combined width greater than the feed mouth, a part of said fingers being in line with the mouth piece and the other part of shorter 100 length being arranged in a position off center in the opposite direction to the direction of rotation of needle cylinder in round knitting and a guide inclining downwardly to the mouth piece for directing the yarn 105 thereto. 90

4. In combination in a latch needle knitting machine having a reciprocating needle cylinder, a mouth piece with downwardly diverging side walls, the lower side of said 110 mouth being wider than the top, the diverging walls serving to open the latches of the needles and a group of thread fingers adapted to feed the yarn across the row of needles from the outer circle of the needles to 115 within the needle row, said group of yarn fingers having a combined width greater than the feed mouth, a part of said fingers being adapted to travel through the mouth piece and others of shorter length arranged in a position off center in the opposite direction to the direction of the rotation of the needle cylinders in round knitting, and a guide inclining downwardly to the mouth 120 piece for directing the yarn thereto. 125

5. In combination in a circular knitting machine, a rotary needle cylinder, a latch opening mouth piece having a front guard or wall to one side thereof, with an inclined guide leading to the mouth piece, and 130

- a series of yarn fingers located in part in rear of said guard and in part in line with the mouth piece, substantially as described.
6. In combination in a stocking knitting machine having a rotary and reciprocating needle cylinder, a latch ring having a thread feed mouth, a yarn finger for feeding the yarn for the heel and toe located substantially radially of the needle cylinder, and a series of yarn fingers arranged off the radial center of the machine and on the side of the heel and toe yarn finger opposite the direction of continuous rotation of the cylinder and to one side of the feed mouth, and means for guiding the yarns from the series of yarn fingers to the mouth, substantially as described.
7. In combination in a stocking knitting machine having a rotary and reciprocating needle cylinder, a latch ring having a thread feed mouth, a yarn finger for feeding the yarn for the heel and toe located substantially radially of the needle cylinder, and a series of yarn fingers arranged off the radial center of the machine and on the side of the heel and toe yarn finger opposite the direction of continuous rotation of the cylinder and to one side of the feed mouth, and means for guiding the yarns from the series of yarn fingers to the mouth, said means consisting of a guard inclining downwardly toward the mouth, substantially as described.
8. In combination in a stocking knitting machine, a cylinder having rotary and reciprocating movements, a latch ring having a narrow yarn feed mouth with downwardly and outwardly diverging latch guards, and with a chamber in rear of said feed mouth enlarged in the direction opposite the direction of continuous knitting, a yarn finger for the heel and toe yarn arranged substantially on the radial center of the machine, and a series of yarn fingers arranged in the laterally enlarged chamber with means for directing the yarns to the feed mouth from said yarn fingers, substantially as described.
9. In combination in a circular knitting machine, a rotary cylinder, swinging yarn feeding means, a plating guide for maintaining in fixed relation the main and plating yarns in knitting and in their travel into and out of feeding position, said guide having an inclined slot for one yarn and an inclined front bar for the other yarn, said incline conforming to the arc in which the feeding means swings.
10. In combination in a circular knitting machine, a rotary needle cylinder, yarn feeding means including a plating yarn finger movably mounted to throw the main and plating yarns into and out of work, a single feed mouth for guiding all the yarns from the feeding device to the needles, and guide means fixed at the mouth piece for maintaining separate the main and plating yarns, substantially as described.
11. In combination in a circular knitting machine, a needle cylinder, pivoted yarn fingers, spring pressed levers bearing on shoulders on the hubs of the yarn fingers to move them down into work, and means for raising the yarn fingers out of work, said yarn fingers having bearing surfaces concentric with their pivots adjacent their shoulders and upon which the spring pressed levers bear when the yarn fingers are raised to neutral position for threading, substantially as described.
12. In combination in a knitting machine, a needle cylinder, a latch ring, a series of yarn fingers pivotally mounted on the latch ring, a series of members bearing on the yarn fingers, compression springs for operating the said members, said spring being compressed as the yarn fingers rise, and means for operating the yarn levers in opposition to the spring pressed levers, substantially as described.
13. In combination in a circular knitting machine, a rotary needle cylinder, a series of yarn fingers arranged as a group approximately radially of the cylinder, a series of pivoted levers of different lengths for operating the yarn fingers and swinging in vertical planes at an angle to the vertical planes of movement of the yarn fingers, said levers having their forward ends reaching substantially to the front of the machine, a post upon which said levers are pivoted in exposed position, a cam shaft at the front of the machine, cam means thereon, cam levers operated thereby, and links extending from the forward ends of the said pivoted levers downwardly, and connected with the cam levers, substantially as described.
14. In combination in a knitting machine, a needle cylinder, pivoted yarn fingers, operating levers of different lengths extending substantially horizontally and swinging in vertical planes at right angles to the vertical planes in which the yarn fingers swing, said levers being pivotally mounted intermediate of their length, sliding lifters between the inner ends of said horizontal levers and the yarn fingers, a pattern drum, levers operated thereby and links connecting the said levers with the outer ends of the horizontal levers, substantially as described.
15. In combination in a circular knitting machine, a needle cylinder, a latch ring pivotally mounted, yarn fingers pivotally mounted on the latch ring, operating levers of different length extending in a direction transversely of and below the yarn fingers, fixed guide means interposed between the operating levers and the yarn fingers, and lifters slidably mounted in the guide means.

and resting upon the ends of the operating levers, said lifters being removable vertically, and being exposed for removal by lifting the latch ring, substantially as described.

16. In combination in a circular knitting machine, a needle cylinder, yarn fingers pivotally mounted, operating levers extending transversely of the planes in which the 10 yarn fingers swing, lifter plates interposed between the operating levers and the yarn fingers, guide means for the lifter plates, said lifter plates engaging the yarn fingers, and having depending projections arranged in echelon and resting upon the operating levers, and means for operating the levers, substantially as described.

17. In combination in a circular knitting machine, a needle cylinder, a latch ring vertically movable, a post with means for detachably connecting said latch ring to the post, yarn fingers pivotally mounted in the latch ring, levers extending horizontally and below the latch ring, lifters between 25 said levers and the yarn fingers, guide means on the post for said horizontal levers and for the lifters and means for operating the horizontal levers, substantially as described.

18. In combination in a circular knitting 30 machine, a needle cylinder, pivotally mounted yarn fingers, operating levers for the yarn fingers extending transversely of the yarn fingers, a post upon which the operating levers are pivotally mounted in exposed 35 position, links connected with the operating levers, pattern means for operating the links, said links having laterally notched heads and the said operating levers having forked ends with rigid pins located in the 40 lateral notches, the heads of said links hav-

ing a portion concentric with the center of the pins and finding a bearing against the bottom wall of the fork of the operating lever to hold the link and lever locked together when they are in operating relation 45 at an angle to each other, and permitting detachment when moved into another relative position, substantially as described.

19. In combination in a circular knitting machine, a needle cylinder, a plurality of 50 yarn fingers, a plurality of operating levers therefor, a post to which the levers are pivotally mounted detachably, a plurality of links for operating the levers, said links having laterally notched heads engaging 55 the pins rigidly fixed in the forked ends of the operating levers, said links and levers being detachable by moving them into a position at right angles to their working positions, the levers and links being arranged 60 outside of the frame of the machine, substantially as described.

20. In combination, a needle cylinder having rotary movement, a series of yarn fingers outside the needle row, a narrow 65 feed mouth piece having inclined latch opening walls diverging from each other downwardly, the group of fingers being arranged off to one side of one of the inclined walls of the mouth piece in a direction opposite to that of the rotation of the machine in round knitting and a guide to direct the yarn to the mouth piece.

In testimony whereof, I affix my signature in presence of two witnesses.

FRANK WILCOMB.
